UNITED STATES PATENT OFFICE

CARL M. PETERSEN, OF TRENTON, NEW JERSEY, ASSIGNOR TO CIRCLE F MFG. CO., OF TRENTON, NEW JERSEY, A CORPORATION OF NEW JERSEY

FLUSH RECEPTACLE

Application filed April 25, 1929. Serial No. 358,050.

This invention has particular reference to improvements in plug receptacles of the so-called flush type.

A primary object of the invention is to provide a receptacle made of moldable insulating material, such for example as bakelite, and which eliminates as far as possible all metallic supporting or carrying parts which require insulation between them and the current conducting parts of the device. Thus, the invention contemplates a practical receptacle construction embodying a minimum number of parts which are strong and durable, inexpensive to produce and in which the assembling operations are greatly simplified, thereby materially enhancing the value of the receptacle from a manufacturing as well as useful standpoint.

Another and more specific object of the invention is to provide a novel molded insulated cover or closure plate for the rear face of the receptacle body, having means for insulating the contact springs and also serving as a key to assist in preventing sideways movement of the cover, as well as carrying means cooperating with the body for securing the cover in place and avoiding breaking or fracturing thereof under pressure of the fastening means.

With the foregoing general purposes in view, the invention consists in the novel features of construction, combination and arrangement of parts as will be hereinafter more fully described, illustrated in the accompanying drawings and defined in the appended claims.

In the drawings, wherein like characters of reference denote corresponding parts in the different views:—

Figure 1 is a front elevation of a plug receptacle constructed in accordance with the present invention.

Fig. 2 is a rear elevation with the backing removed.

Fig. 3 is a central longitudinal sectional view of the receptacle.

Fig. 4 is a transverse section on the line 4—4 of Fig. 1.

Fig. 5 is a transverse section on the line 5—5 of Fig. 1.

Fig. 6 is a plan view of the backing member looking towards the inner face thereof; and

Fig. 7 is a view similar to Figs. 4 and 5 illustrating an alternative embodiment of 55 backing reinforcing means.

As previously indicated the present invention aims to provide a receptacle wherein insulating material is used to advantage to secure the necessary strength for the receptacle body as well as the cover therefor, thereby avoiding the use of metallic supports or straps as heretofore proposed in the art. 60

For example, in a form of receptacle now in use there is employed an insulating body recessed for the reception of contacts and closed at its rear face by a sheet of insulation which is maintained in assembled relation with the body by a metallic strap. This strap ex- 65

extends over the ends of the body and terminates in ears which receive fastenings for mounting the entire assembly in an outlet box. This construction however, is open to various objections particularly from a manufacturing standpoint, as it embodies an exces- 70

sive number of parts more or less difficult and expensive to produce and assemble. The present invention therefore has in view to simplify the construction and reduce the cost 75

of plug receptacles of the foregoing type by 80 providing a molded insulating backing for the plug body, by providing securing means for said backing which eliminates the necessity of providing any form of holding strap therefor, and by providing simple means, 85

entirely independent of the backing and its

securing means, for mounting the receptacle in an outlet box.

Accordingly, the present invention contemplates in its general organization a one-piece, molded insulating body provided with a contact chamber or chambers opening through the rear face thereof, contacts disposed within said chamber or chambers, a one-piece, molded insulating cover or back- 90

ing for closing the rear face of said body, simple yet efficient means for securing the cover in assembly with the body, and sep- 95

arate means for mounting the body in an out-

let box. 100

Referring to the drawings in detail, A designates generally the body of the present plug receptacle and B the backing or cover for the rear face thereof, the body A being constructed to accommodate two sets of receptacle contacts arranged in parallel in a single fitting, and the backing B being constructed to provide a common closure for both sets of contacts.

10 In accordance with common practice the body A is molded from insulating material to provide a pair of bays 10, 10 and a web 11 connecting them, the outer face of the web being depressed whereby the outer portions 15 of the bays constitute bosses adapted to be received in similarly shaped openings in a face plate 7.

Formed integrally with and extending rearwardly from the bays 10, 10 and the web 20 11 is an elongated, rectangularly-shaped, box-like structure 12 consisting of side walls 13 and end walls 14. Near the end walls of this box-like structure the side walls thereof are connected together by partition walls 15, 25 while connecting each of these partition walls with its related end wall 14 is a partition wall 16. The result is that a pair of contact chambers 17 is provided at each end of the box-like structure 12, which chambers 30 are disposed in alignment with contact finger receiving slots 18 formed in the bays 10, 10. In addition, each of the side walls 13, intermediate its ends, has a slot 19 formed therein and opening through the rear edge thereof.

35 The two metallic contact elements of the present plug receptacle are duplicates of one another, each consisting of a strap 20 provided at each end thereof with a contact finger 21 and, intermediately thereof, with a 40 terminal ear 22 provided with a binding screw 23. Said ear and said fingers are formed at opposite side edges of the strap and are bent to extend in the same direction at substantially right angles to the plane of 45 the strap. In assembly, the straps 20 lie with their outer edges contiguous to the inner faces of the side walls 13 of the box-like structure 12, and with their rear faces flush with the rear face of said box-like structure, 50 the rear edges of the partition walls 15, across which said straps extend, being depressed to accommodate said straps. The terminal ear 22 of each strap lies against the outer face of its related side wall 13, the 55 binding screw 23 being accommodated by the slot 19 in-said wall, and the contact fingers 21 being disposed, respectively, within corresponding chambers 17 at opposite ends of the box-like structure 12.

60 The backing or cover B in accordance with the present invention is molded from insulating material. It is of one-piece construction and of such size and shape that when placed in covering relation to the rear face of the box-like structure 12 its side edges

are disposed flush with the outer faces of the side and end walls 13 and 14 of said box-like body. Formed integrally with said backing and projecting from the inner face thereof is a rib 24 of such length as to fit neatly at its ends between the adjacent faces of the partition walls 15, 15, and of such width as to fit neatly between the adjacent edges of the contact straps 20. Thus, this rib by co-operation with the partition walls 70 15 and the contact straps 20 holds the backing 75 against any movement in the plane thereof with respect to the box-like structure 12.

Any suitable means may be employed to secure the backing B in covering relation to the rear face of the body portion 12. In the present instance a post 25 is embedded at one end in the material of the backing during the process of molding the backing, the embedded end of said post being headed or flanged as 80 indicated at 26 whereby it is incapable of being pulled from the backing without fracturing or shearing the latter. Said post is located centrally of the backing, extends forwardly from the rear face thereof, and at its 85 free end is bored and internally threaded. An opening 27 is formed through the web 11, and when the backing is disposed against the rear face of the body portion 12 the free end of the post 25 projects into this opening, the backing being secured in assembly with the body A by spinning over the outer end portion of the post against an outer portion of the web 11, said web preferably being suitably recessed to receive the spun 90 over portion of the post whereby the outer end of the latter lies flush with or inwardly of the outer face of said web.

In order to eliminate the possibility of the post 25 being pulled from the backing by 105 excessive tightening of the screw 28 which is threaded into the post 25 and provided to secure the face plate in assembly with the body a sleeve 29 is provided to surround the post between the adjacent faces of the web 11 and the backing, this sleeve constituting a compression member through which any longitudinal pulling force exerted through the post by the screw 28 is transmitted from the head 26 of the post through the material 110 of the backing and said sleeve to the inner face of the web 11. Thus, when the screw 28 is tightened the small amount of material between the head 26 of the post and the inner face of the backing is reinforced by the sleeve so that said material is subjected only to compressive strains, pulling of the post from the backing under such conditions being practically impossible.

120 The sleeve 29 may be formed as an element separate from the body A and the backing B as shown in Figs. 3 and 5, or it may be formed as an integral part of either the body A or the backing. In Fig. 7 it is illus- 125 130

trated as being formed integrally with the backing B.

By reason of the foregoing method of securing the backing B in assembly with the body A the necessity of any form of backing securing strap extending across the rear face of the backing is eliminated as is manifest.

According to the present invention very simple, inexpensive and efficient means is provided for mounting the plug receptacle as an entirety in an outlet box. It will be noted that the bays 10, 10 extend outwardly beyond the ends of the box-like structure 12 and that in accordance with the present improvements headed rivet inserts 30 are embedded in the extended portions of said bays. The outer end portions of these rivet inserts are reduced in diameter as indicated at 31, thereby providing shoulders which lie flush with the inner faces of recesses 32 formed in the extending portions of the bays. Metallic ears 33 of a width to fit neatly in said recesses with their inner ends abutting the outer faces of the end walls 14 of the body portion 12, are provided with apertures to receive the reduced ends of the rivet inserts, which latter, following positioning of said ears in said recesses, are headed over against the outer faces of the ears thereby to rigidly secure the latter to the body A. Said ears extend outwardly from said body and are apertured as at 34 to receive screws or other fasteners for securing the receptacle in an outlet box in a manner which is well known.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

- 45 1. A plug receptacle inclusive of a molded insulating body, contact means carried by said body, a molded insulating backing for covering the rear face of said body, a rib molded integrally with said backing cooperating with said contact means to prevent movement of said backing in the plane thereof relatively to said body, and means for securing said backing in covering relation to the rear face of said body.
- 50 2. A plug receptacle comprising a body recessed from its rear face to provide a contact chamber, a backing for closing the rear face of said body, a member secured to the backing, a wall plate for cooperation with the front of the body, and a screw extending through said wall plate and threaded into said member to detachably secure the wall plate in assembly with the body.
- 55 3. A plug receptacle comprising a body recessed from its rear face to provide a con-

tact chamber, a backing for closing the rear face of said body, a post secured at one end to the backing for securing the backing in assembly with the body, a wall plate for cooperation with the front of the body, and a screw extending through said wall plate and threaded into said post to detachably secure the wall plate in assembly with the body.

In testimony whereof I hereunto affix my signature.

CARL M. PETERSEN.
